STREAM-OR-SPRAY GUN

Arthur J. Kunz, Prospectville, Pa.

Application February 26, 1942, Serial No. 432,491

6 Claims. (Cl. 299—144)

This invention relates to a relatively light portable device for selectively training either a solid stream or a fine spray of aqueous fluid on a target, such as an incendiary bomb, for example, although the device is adapted for general use wherever such a selection of discharge may be desirable, as in the fighting of forest fires, application of insecticide to trees, shrubs, chicken houses, or disinfectants to exposed or obstructed places in attics, cellars, closets, or other parts of domestic dwellings, industrial establishments, hospitals, jails and so forth.

One object of the invention is to construct the device in such a manner that it will normally produce the spray discharge, to prevent accidental playing of a solid stream of water on a bomb by any excited person picking the device up for use against burning incendiaries, which may cause the bomb to explode.

Another object of the invention is to provide the device with a manually operable control valve which must be intentionally actuated to change from the spray discharge to the solid stream discharge; and to place the control handle for the valve in such a position with respect to the main handle of the device as not to be grasped and operated unintentionally in the excitement and haste of initiating discharge of fluid when a bomb is encountered.

Another object of the invention is to arrange the nozzles from which the spray and stream are respectively discharged, at divergent angles to each other, in order that the gun will have to be reaimed at the target when it is desired to train the solid stream thereon, whereby the trajectory of the solid stream would carry the fluid above or wide of a burning incendiary should an excited operator suddenly reach for and unconsciously actuate the handle of the control valve and unintentionally discharge the solid stream instead of the spray from the gun.

Another object of the invention is to construct the device in such a manner that it can be held, aimed, and operated, for stream or spray discharge in or by the use of only one hand, leaving the other hand of the operator free to actuate a stirrup pump, or to hold a protecting blanket or other shield in front of his body or face as he approaches the bomb within effective range of the gun, which, for example, would preferably be approximately ten feet for the spray and thirty feet for the solid stream.

The construction and operation of the device will be fully disclosed hereinafter, reference be-

ing had to the accompanying drawings, of which:

Fig. 1 is a pictorialization of the device in use, showing the discharge of a spray of fluid toward and around a burning incendiary, and illustrating, in broken lines, the trajectory of the stream, if and when the control valve is actuated to discharge the stream without changing the position of the gun;

10 Fig. 2 is an enlarged sectional view of the main body of the gun, showing the control valve in its normal released position to effect the spray discharge automatically;

15 Fig. 3 is a view similar to Fig. 2 with the valve moved to a position for effecting the stream discharge;

Fig. 4 is a view similar to Fig. 2, showing the valve in position to eliminate all discharge;

20 Fig. 5 is a sectional view of the spray discharging nozzle;

Fig. 6 is a sectional view of the stream discharging nozzle; and

Fig. 7 is a view of a modified form of the invention.

25 As shown in the drawings, the device comprises a main body 1, having a handle 2 extending from one of its sides and a pair of tubes 3 and 4 extending from its opposite side.

As shown in Fig. 1, the tube 3 is of relatively 30 shorter length than the tube 4, with the portion 4a of the tube 4, which lies adjacent the body 1, arranged with its axis substantially parallel to the axis of the shorter tube 3, and with the outer portion 4b of the tube 4 arranged with its 35 axis at an acute angle to the axis of the tube 3.

The outer end of the tube 3 (Fig. 6) is provided with a readily detachable nozzle 5 having a smooth through bore 6 for discharging aqueous fluid in the form of a solid stream, and with 40 a readily removable screen 7 for preventing foreign solid matter from getting into and clogging the bore 6.

The outer end of the portion 4b, of the tube 4 (Fig. 5), is provided with a readily detachable 45 nozzle 10 having a through small bore 11 adapted to impinge liquid against a baffle 12 carried by the nozzle 10, for breaking up a stream from the bore 11 into a fine spray, as shown in Fig. 1.

Obviously any other form of spray producing 50 nozzle may be substituted for the particular one shown in the present case without departing from the spirit of the invention.

As shown in Fig. 5, the tube 3 is also provided with a readily removable screen 13 for preventing 55 foreign matter from clogging the nozzle 10.

The handle 2, in the present instance, is also in the form of a tube or is provided with a central longitudinal bore 14 for passage of liquid from a suitable source into the body 1, for direction into either the tube 3 or the tube 4.

The outer end of the handle 2 is provided with a readily detachable hose coupling 15 and a readily removable screen 16, by which latter foreign matter is prevented from entering the body 1.

The body 1 is provided with a bore 19 in which is slidably mounted, for axial movement, a control valve 20.

As shown in Figs. 2 to 4 inclusive, the bore 19 of the body 1, communicates with ports 21, 22 and 23 leading to the bores of the handle 2, tube 3 and tube 4 respectively, with the port 21 located equidistantly between the ports 22 and 23, axially of the bore 19.

The control valve 20 is in the form of a piston of sufficient length, as shown in Fig. 4, to be intermediate and clear of both discharge ports 22 and 23, while completely closing the inlet port 21.

When the valve 20 is depressed, as shown in Fig. 3, its upper end lies below the inlet port 21 and permits passage of fluid from said inlet port, upwardly through the bore 19 and into the discharge port 22 for passage into and through the stream tube 3.

When the valve 20 is raised, as shown in Fig. 2, its lower end is above the inlet port 21, permitting fluid to flow into and downwardly through the bore 19, from the inlet port 21 into the discharge port 23 and thence to the spray tube 4.

The valve 20 is automatically raised to the spray producing position of Fig. 2, by a spring 24, located in the lower end of the bore 19; and is adapted to be manually depressed into its "shut-off" position of Fig. 4, or its stream producing position of Fig. 3, by a lever 25 having a thumb plate 26 on its outer end, which normally lies in a relatively high position above the handle 2 and close to the side of the body 1 so as to be out of the way when the gun is grasped hurriedly for action.

The piston valve 20 is provided with a stem 27 which passes through a packing gland 28 carried by the upper end of the valve cylinder provided by the body 1 of the device.

The end of the lever 25, opposite the thumb pad 26, is pivotally connected by a link 29 to the body 1 or to the upper tube 3, with the lever adapted to be pivoted to or slidably within a head 30, preferably the latter, so that the lever may be moved into a position outwardly from the body 1, over the handle 2, as shown in Fig. 3, for example.

In order to hold the valve 20 in its "shut-off" position of Fig. 4, any suitable catch may be provided, such as the latch 31 shown in said figure to catch the lever 25 or its thumb pad 26.

Preferably a spring 32 is provided to move the latch 31 to and hold it firmly in its inoperative position of Figs. 2 and 3, in order to prevent the latch from catching the lever 25 and preventing it from permitting the valve 20 to return automatically to its spray position of Fig. 2, when released from its stream position of Fig. 3.

The underside of the head 33 of the latch 31 is undercut at 34, on an upwardly inclining angle to grip a reversely inclined shoulder 35 on the heel of the thumb pad 26, so that the upward pressure exerted on the lever 25 by the valve spring 24 will overcome the lateral force exerted

on the latch by its spring 32 and maintain the latch in place.

The latch 31 is readily released by a slight downward pressure applied to the thumb pad 26, which permits the spring 32 to swing the latch to its inoperative position by the undercut 34 of the latch slipping off the shoulder 35 of the thumb pad.

To bleed out fluid trapped in the lower end of the valve cylinder 1, between the closed end 36 thereof, and the lower end 37 of the piston valve 20, the stem 27 is bored axially and laterally, as shown at 38 and 39 respectively. This arrangement also serves to bleed out fluid trapped between the upper end 40 of the piston 20 and the underside 41 of the packing gland 28, so that the valve 20 will move quickly from one to another of its fluid controlling positions.

Preferrably the handle 2 of the device is insulated, electrically, to prevent shock to the operator in the event of the stream or spray impinging upon a bare live wire which might be torn loose and exposed by the bomb being fought. For this purpose the handle 2 is preferably provided with a sleeve 42 of dielectric material, such as rubber, Bakelite etc. The lever 25, and latch 31 for similar reasons are preferably insulated either by coating with or being formed of dielectric material.

If desired the lever 25 may be replaced by a knob 45 on the upper end of the valve stem 27, as shown in Fig. 7.

I claim:

1. A hand device for discharging fluid at a definite target, comprising a body portion, a handle projecting from said body portion, a pair of tubes extending from said body portion, a spray nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, a lever extending transversely across said stem and including a finger pad at one end lying above said handle, and means pivotally connecting the opposite end of the lever to said body.

2. A hand device for discharging fluid at a definite target, comprising a body portion, a handle projecting from said body portion, a pair of tubes extending from said body portion, a spray nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, a lever extending transversely across said stem and including a finger pad at one end lying above said handle, means pivotally connecting the opposite end of the lever to said body, and a spring for moving said lever in the direction of its length to hold said pad in position adjacent said stem.

3. A hand device for discharging fluid at a definite target, comprising a body portion, a handle projecting from said body portion, a pair of tubes extending from said body portion, a spray nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, a lever extending transversely across said

stem and including a finger pad at one end lying above said handle, means pivotally connecting the opposite end of the lever to said body, and a latch for engaging the pad end of the lever to retain the valve in position preventing flow to either of said tubes.

4. A hand device for discharging fluid at a definite target, comprising a body portion, a handle projecting from said body portion, a pair of tubes extending from said body portion, a spray nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, a lever extending transversely across said stem and including a finger pad at one end lying above said handle, means pivotally connecting the opposite end of the lever to said body, a latch for engaging the pad end of the lever to retain the valve in position preventing flow to either of said tubes, and a spring for normally retaining said latch in an inoperative position out of the path of said lever.

5. A hand device for discharging fluid at a definite target, comprising a body portion, a handle projecting from said body portion, a pair of tubes extending from said body portion, a spray

nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, means resiliently projecting said stem beyond said body, and a finger pad for depressing said stem to actuate said valve in opposition to said resilient projecting means.

6. A hand device for discharging fluid at a definite target, comprising a body portion, a handle projecting from said body portion, a pair of tubes extending from said body portion, a spray nozzle carried by the outer end of one of said tubes, a stream nozzle carried by the outer end of the other of said tubes, a plunger valve slidably mounted in said body to control the flow of fluid to said tubes selectively and including a stem extending axially beyond the upper end of said body, means resiliently projecting said stem beyond said body, a finger pad for depressing said stem to actuate said valve in opposition to said resilient projecting means, and a latch for engaging said finger pad to hold said valve in a predetermined position to prevent flow of fluid to either of said tubes.

ARTHUR J. KUNZ.
